UNITED STATES PATENT OFFICE

139,504

DESIGN FOR A FOOTREST

Sabra S. Sadler, Richmond, Va.

Application October 4, 1944, Serial No. 115,607

Term of patent 14 years

(Cl. D15—8)

To all whom it may concern:

Be it known that I, Sabra S. Sadler, a citizen of the United States, residing at Richmond, in the State of Virginia, have invented a new, original, and ornamental Design for a Footrest, of which the following is a specification, reference being had to the accompanying drawing, forming part thereof.

In the drawing:

Fig. 1 is a top perspective view of a footrest showing my new design.

Fig. 2 is a bottom perspective view thereof.

I claim:

The ornamental design for a footrest, as shown.

SABRA S. SADLER.
